UNITED STATES PATENT OFFICE.

GEORGE B. KEPLINGER, OF CHICAGO, ILLINOIS, ASSIGNOR TO CRUVER MANUFACTURING COMPANY, OF CHICAGO, ILLINOIS A CORPORATION OF ILLINOIS.

POCKET SAVINGS BANK.

Application filed April 15, 1921. Serial No. 461,518.

To all whom it may concern:

Be it known that I, GEORGE B. KEPLINGER, a citizen of the United States, and resident of Chicago, in the county of Cook and State of Illinois, have invented certain new and useful Improvements in Pocket Savings Banks, of which the following is a specification.

My invention relates to improvements in containers and has special reference to improved means for locking and releasing container covers, particularly the covers of coin containers such as small savings banks.

The object of my invention is to provide a simple means for locking the cover or top 15 on a container such as a coin box, which means shall occupy but a minimum of depth or space; which shall simulate a combination or permutation lock; which shall be simple and cheap in construction; which shall prevent 20 no protuberances or projections to the coin or other contents; which shall be so constructed that when the cover is locked to the box it can be turned indefinitely in either direction without unlocking the cover; and 25 which shall be readily unlocked by the application of a novel key.

One important feature of my invention relates to a novel key for application to the box and which once applied is automatically 30 projected into the operating or locking mechanism upon the rotation of the cover in the right direction and automatically releases itself if turned in the wrong direction.

Another important feature of my invention 35 relates to the provision of a coin slot guard which readily allows coins to enter into the box but which automatically closes against the ejection of coins.

My invention resides in a bank preferably 40 in the form of a circular box one end of which constitutes a cover and which is removable, the cover having a plurality of L-shaped lugs by which it is secured to the box and which are adapted to enter thru notches 45 in the top of the box and engage with the locking mechanism. The locking mechanism comprises a rotatable member provided with notches for permitting the entrance of the lugs when registered with the notches in the 50 top of the box, together with means for locking the cover to the rotatable member with its lugs out of register with the notches in the rotatable member and which is so arranged that it prevents the escape of the 55 lugs thru the notches in the top of the box

even when brought into alignment therewith. The key is adapted to release the lugs from the rotatable member, to cause the rotatable member to register with the notches in the top of the box and permit the independent rotation of the cover to cause its lugs to register with the notches in the rotatable member and with those in the top of the box for the removal of the cover.

One of the rings of the rotatable locking member forms a guard cover to protect the lugs and the other ring and is provided with an internal flange adapted to contact with the cover member radially within the lugs to prevent the pressure or thrust of the coins 70 binding the rotatable rings which are preferably made of thin sheet metal.

A further important feature relates to the provision of a spring member for locking the cover thru its lugs to the rotatable member, 75 one end of this spring is provided with a rounded projection adapted to yieldingly engage the wall of the box and produce some light yielding frictional resistance to the free rotation of the locking ring. The rotatable guard member is adapted to be held in place against the top of the box by means of the coin guard at one point and a plurality of legs or projections struck up out of the bottom of the box at other points. This 85 guard ring is void of any projection and presents a smooth continuous surface to the interior of the box that is to the contents except only for a single relatively short slot thru which the key is adapted to enter and 90 also protects the contents from contacting with the cover lugs.

The coin slot guard is very simple in construction, the yielding members being made of flat spring metal and are so supported 95 that the yieldable means is free to permit the coins to enter but is supported by the casing of the box so that it cannot yield in the opposite direction to permit the coins to be discharged through the slot.

My invention will be more readily understood by reference to the accompanying drawings forming part of this specification and in which:—

Figure 1 is a side elevation of a container 105 in the form of a small savings bank embodying my invention;

Figure 2 is a vertical transverse section on the line 2—2 of Figure 1;

Figure 3 is a fragmentary section similar 110

- 2
- to Figure 2 but taken on the line 3—3 of Figure 9;
- Figure 4 is a fragmentary vertical section similar to Figure 2 but taken on the line 5 4—4 of Figure 7;
- Figure 5 is a section similar to Figure 4 but showing some of the parts in different positions;
- Figure 6 is a top plan view of the bank 10 with the cover removed;
- Figure 7 is a fragmentary plan view similar to Figure 6 illustrating the registration of the notches thru which the cover lugs pass in and out;
- 15 Figure 8 is a horizontal section on the line 8—8 of Figure 2;
- Figure 9 is a horizontal sectional view on the line 9—9 of Figure 2;
- Figure 10 is a side elevation of the coin 20 slot guard as seen from the outside as indicated by the arrow 10 on Figure 2;
- Figure 11 is a similar inside view of the coin slot guard indicated by the arrow 11 on Figure 2;
- 25 Figure 12 is a plan view of one of the torsion springs used on the coin slot guard, before being formed to fit upon the support;
- Figure 13 is a view similar to Figure 12 but of a modified form of torsion spring 30 plate;
- Figure 14 is an enlarged vertical sectional view similar to Figure 2 particularly illustrating the coin slot guard and its operation;
- 35 Figure 15 is a horizontal sectional view similar to Figure 8 showing the novel key which I have devised and is shown in operative relation to the bank;
- Figure 16 is a fragmentary vertical sectional view on the line 16—16 of Figure 15;
- 40 Figure 17 is a fragmentary vertical sectional view on line 17—17 of Figure 16, showing the operative part of the key in operative position;
- 45 Figure 18 is a view similar to Figure 17 showing the operative part of the key within the bank but before it has entered or turned into operative position;
- Figure 19 is an end elevation of the key 50 taken in the direction of the arrow 19 on Figure 15;
- Figure 20 is a bottom plan view of the cover showing the cover lugs;
- Figure 21 is a bottom plan view of the 55 tumbler rings before it is assembled with the guard ring; and
- Figure 22 is a view similar to Figure 4 showing a modified form of guard and tumbler rings.
- 60 In said drawings, 1 represents the container which in the form shown is a flat cylindrical box comprising a cylindrical shell 2 closed at its lower end by means of a bottom 3 and provided at its upper end with an in- 65 turned horizontal flange 4 providing a cen-

tral opening 5 thru which the contents of the container can be removed. The opening 5 is closed by means of a cover 6 having an inner plate 6' provided on its under side with L-shaped lugs 7 adapted to enter into 70 the container beneath the flange 4 and be engaged with suitable locking devices for retaining the cover upon the box. The bottom 3 is formed outwardly as shown at 8 and the box is finished and the bottom is 75 covered by means of a plate 9 having an annular flanged edge 10 and the plate 9 and its edge 10 is overlaid by a sheet 11 of finishing material such as celluloid the edge of the piece of celluloid being bent around 80 the edge 10 and held between the edge 10 and the lower edge of the box. Likewise the cover 6 is recessed as shown at 12 and is likewise covered and finished by means of a plate 13 similar to the plate 9 which is 85 likewise overlaid by affixing a sheet 14 of celluloid or other suitable finishing material the edge of the sheet 14 being bent around the edge 15 of the cover sheet 13 and clamped between the edge 15 and the outer edge of the cover 4 as best shown in Figure 14. The celluloid cover 14 is provided with suitable division marks 16 on its edge and the body of the box is provided with an indicator 17 so that as the cover 90 is turned upon the box it will simulate and can be used in the same manner as an index plate such as is ordinarily used with a combination or permutation lock. This feature is only for effect and not for its use. Between the cover and the bottom 3 the side wall of the box is provided with a circumferential coin slot 18 thru which coins can be introduced into the box or bank. 100

Special novel features of my invention 105 relate to the means for interlocking the cover with the body of the box and with the means for guarding the coin slot to prevent the removal of coins from the bank thru the coin slot.

For the purpose of interlocking the cover 4 with the box I provide the flange 4 with a plurality of notches 19 in its inner edge spaced circumferentially the same as the cover lugs 7 and of a size to permit the 110 easy passage of the lugs 7 thru the flange 4 and the lugs 7 are long enough so that when the cover is placed upon the box and the lugs are passed thru the notches 19 the out turned prongs or feet 20 of the cover lugs 7 extend and are located in a plane a 115 short distance below the flange 4 so that they can rotate beneath the flange as the cover is rotated. I provide means beneath the flange comprising a rotatable locking ring which is adapted to close the notches 19 after the cover lugs have passed thru and prevent the withdrawal of the cover lugs and the removal of the cover. This 120 locking or tumbler ring comprises a ring 125 130

21 shown in plan view in Figure 21 and consists of a flat ring-like member having an outer cylindrical flange 22 and a narrower flange 23 at its inner edge. The 5 outer flange 22 or rather the ring itself is of an external diameter to fit the cylindrical wall 2 of the container and the flat surface 24 of the ring 21 is adapted to contact with the under surface of the flange 10 4 and the ring is adapted to rotate in such position. This ring is likewise provided in its inner edge with notches 25 adapted to be registered with the notches 19 to permit the cover lugs to pass thru so that 15 the horizontal projecting ends 20 of the cover lugs can rotate beneath the flat ring 21 as best shown in Figure 5. In the form shown both the flange 4 and the ring 21 are each provided with three of the notches 20 equally spaced circumferentially to receive the three cover lugs.

Beneath the ring 21 I provide a second ring 26 having an upturned cylindrical flange 27 at its inner edge adapted to rise 25 into contact with the cover 5 the main portion 28 of the ring 26 having an external diameter equal to the internal diameter of the casing and adapted to rotate freely therein. The ring 26 is adapted to guard 30 the locking mechanism to prevent the thrust or pressure of the coin bending or distorting same and also to guard or protect the coin against contact with the cover lugs as the flange 27 extends upwardly radially 35 within the cover lugs forming a channel 29 immediately within the inner edge of the flange 4 around which the vertical portions 30 of the cover lugs can travel as the cover is rotated upon the box. The tumbler ring 40 21 and the guard ring 26 are adapted to be permanently interlocked together by means of tongues 31 struck up at the outer edge of the ring 26 the outer inclined surfaces of which are engaged by tongue portions 32 45 of the flange 22 which are turned inwardly and interlock therewith the outer edge of the ring 21 bears upon the lower edge of the flange 22 throughout its circumference except at the points where the interengaging 50 projections 31 and 32 are formed. The thrust of the coin is taken at the inner edge of the ring by the cylindrical flange 27 in contact with the cover and at the outer edge by the flange 22 of the ring 21. The 55 ring 21 and the ring 26 are spaced apart to provide a flat ring-like space 32 for accommodating the cover lugs and containing the locking mechanism. Both of the rings 21 and 26 are made of quite thin sheet metal 60 but in the form in which I make the rings with the flanges at the edges or bound against the flanges they are relatively stiff and rigid and for the purpose of increasing the rigidity and strength of the ring 21 I 65 provide the shallow flange 23 at its inner

edge which is down turned. As best shown in Figure 21 portions of this flange 23 are cut away adjacent to each notch 25 or rather this portion of the flange is flattened down as best shown in Figure 21 forming shoulders 34 substantially half way between the notches 25 and against which the cover lugs 7 are adapted to contact and I provide means for automatically locking the cover lugs in contact with the shoulders 34 so that 70 once the cover has thus been interlocked with the rotatable member the lugs are positioned beneath the ring 21 and cannot rise thru the notches 19 in the flange 4 in the top of the box until released from such position and moved relatively to the ring 21 back to positions where they can pass upwardly thru the notches 25 in the ring 21. 75

For the purpose of interlocking the cover lugs 7 with the rotatable tumbler or rotatable member comprising the guard ring 26 and the tumbler ring 21 I provide a spring member 35 carried by the ring 21 and adapted to lie within the space 32 and having a shoulder or an offset providing a 80 shoulder 36 against which one of the lugs 7 is adapted to contact, the lug being thereby held against one of the shoulders 34 formed by the ends of the portions of the flange 23 on the ring 21 which are not turned down. 85 At one side of the shoulder 36 the spring 37 extends outwardly on an angle towards the outer flange 22 of the ring 21 and its extreme end 38 is confined against said flange by means of a struck up lug 39 90 formed out of the ring 21. The opposite end of the spring extends around the ring 21 and is provided with a curved portion or hump 40 which extends inwardly to contact with the flange 23 and form a shoulder 95 41 which contacts with a struck up lug 42 formed out of the ring 21 to prevent movement of the spring in one direction. Beyond the hump 40 the spring extends further around the ring 21 and is provided at 100 its extreme end with a curved projection 43 adapted to project thru an opening 44 in the outer flange 22 of the ring 21 and contact with the inner cylindrical surface of the casing thus providing a frictional engagement of the rotatable member with the casing which prevents its free rotation and tends to retain it in the position in which it is placed by means of the cover lugs. The 105 long inclined portion of the spring 35 between the shoulder 36 and the end 38 permits one of the cover lugs 7 to push the spring outwardly as indicated in dotted line in Figure 8 and progress past the shoulder 36 into contact with the shoulder 34 on the flange 23 at which time the spring by its resiliency is forced in and the cover lug 7 is locked between the two shoulders and thereafter the rotatable member rotates with the cover and the lugs 7 cannot pass thru 110 115 120 125 130

the notches either in the ring 21 or the flange 4 until the engaged lug is released from its interlocked position.

As shown in Figures 15 to 19 inclusive I provide a simple and novel key for unlocking the engaged lug 7 from its interlocked condition with the rotatable member. For the purpose of applying the key to release the cover I provide the guard ring with a slot 45 in its bottom 26 at the part opposite to the inclined portion 46 of the spring 35 and across which said portion of this spring is inclined as best shown in Figure 15. This slot is adapted to admit a prong 47 of a key 15 when the rotatable member is rotated in the proper direction the prong 47 entering the slot 45 at the end adjacent to the outer end of the spring 35 and then as the rotatable member is rotated this prong engages the 20 inclined portion 46 of the spring and forces the spring outwardly far enough to release the cover lug 37 from the shoulder 36 of the spring and permit the cover to rotate relatively to the rotatable member and register 25 its lugs with the notches and thus release the cover.

The prong is formed upon the inner end of a key member 48 which is preferably made of wire and for the purpose of allowing the 30 prong 47 to automatically enter into the slot 45 when the rotatable locking member is rotated to the proper position I mount the key member 48 in a carrier or handle 49 having a tail portion 50 formed to engage the 35 lower edge of the box and provided with two vertical parallel flanges 51 and 52 having suitable notches in their upper edges for receiving the wirelike key 48. For holding the key against endwise movement I secure a 40 tubular member 49 on the body of the key between the flanges 51 and 52 thus forming shoulders for contact with the flanges and I provide the handle member with an end wall 54 adapted to be formed over the key member 45 and hold it against rising out the notches formed in flanges which receive it. I provide the key member with a ring handle 55 its inner part sweeping past the outer flange 51 and adapted to contact with stop lugs or 50 projections 56 and 57 to permit the key to rotate thru the substantially 90°. The key is normally held against the stop lug 57 by means of a spring 58 carried by the key and in such position the projection 47 is vertical. One end of the spring 58 is secured to the key 48 and its opposite end is bent around the lug 57. When the key is rotated to bring the handle 55 into contact with the stop 56, as shown by dotted line in Figure 55 19, the projection 47 is horizontal. In applying the key it is turned to the dotted position shown in Figure 19 and then the inner end carrying the projection 47 can be entered into the bank thru the coin slot 18 and 65 then the key is released and the spring op-

erates to turn the key and cause the free end of the projection 47 to contact with the lower surface of the rotatable member as best shown in Figure 18 in position when the slot 46 is brought around to the proper position by the rotatable member being rotated by means of rotating the cover, to enter the slot 46 and as the rotatable member is rotated further to cause the withdrawal of the spring 35 so as to release the cover lug 7. 70 In positioning the key for unlocking the box the key proper is positioned at one end of the key slot and in this position it serves as a stop contacting with the farther end of the slot 46 to cause the notches 25 in the tumbler 75 ring to properly register with the notches 19 in the flange 4 so that when the cover lug 7, which is engaged between the shoulder 37 on the ring 21 and the shoulder 36 of the spring, is released the cover can be rotated 80 to cause the several lugs to register with the notches so that the cover can then be readily removed.

In unlocking the box the procedure is as follows, the key 48 is rotated so that the projection 47 is horizontal and then it is applied to the bank as described and the key 48 is then released and the cover is turned in the direction of the arrow on Figure 15 until the projection 47 enters the slot 46 and the cover is then further rotated in the same direction until the projection 47 pulls the spring 35 back and releases the cover lug 7 at which time the notches in the rotatable member register accurately with the notches 90 in the flange 4. As the lug 47 is released the spring contact formed by the projection 43 of the spring against the casing holds the rotatable member against further rotation and the cover is rotated free of same until the 95 lugs 7 are registered with the notches and the cover can be freely lifted off. In such registration of the cover lugs 7 they contact with the opposite shoulders or ends 59 of the segments of the flange 23 which are adjacent 100 to the notches 25 in said flange or ring. The shoulders 59 on the ring 21 serve to cause the cover lugs 7 to register accurately with the notches in the ring 21 upon the rotation of the cover relatively to the ring after being 105 released therefrom. If it occurs that the ring is carried along slightly with the cover in this reverse rotation, the spring drag on the ring 21 will hold it back and cause the cover lugs to contact with the shoulders 59 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 of the bottom 3 of the box and adapted to rise from the bottom of the box close to the cylindrical wall 2. As best shown in Figure 9, these legs or supports rise into contact with the bottom surface of the ring 26 but do not bind the ring between the tops of the legs and the flange 4 leaving the rotatable member freely rotatable. In place of one of the legs 59 I may make use of my novel coin slot guard which I provide for permitting the introduction of the coins through the slot 18 and preventing the removal of the coin thru the slot.

This novel coin slot guard designated generally by 60 comprises a sheet metal support 61 conformed to the cylindrical wall 2 of the casing and secured by foot lugs 62 to the bottom 3 of the casing and arranged just within the slot 18. The end portions 63 of the support 61 are wide enough to contact with the bottom plate 3 and rise to the underside of the rotatable member and thereby constitute a support therefor if such is desired. The middle portion of the support 25 61 is cut away forming a slot 64 arranged opposite to and in registry with the slot 18 and thru which the coins can enter past the support 60 to the box. The upper and lower bars 65 and 66 forming the upper and lower edges of the slot 64 are bent or formed inwardly at their adjacent edges 67 as shown in Figure 14 so that these two bars are inclined inwardly at an angle of substantially 30° to the outer wall of the box. The slot 35 64 is wider than the thickest coin which the box is adapted to receive and I provide a yieldable guard carried by the support 61 adapted to yield to permit the insertion of the coins and to automatically prevent the ejection or removal of the coins thru the coin slot. For this purpose I provide two spring members 67 secured to the support 61 and carried thereby. These members are each made of flat spring sheet metal as best 40 illustrated in Figure 12 and each is provided with two longitudinal arms 68 at one end and with a slot 69 at the other end. Each end of the support 61 is provided with a tongue 70 which is adapted to be received 45 in the slot 69 of one of the spring members to secure them to the support as best shown in Figures 10 and 11. The arms 68 are adapted to lie co-incident with bars 65 and 66 and their free ends 71 are arranged adjacent to the middle portion of the coin slot 50 18 but spaced apart as shown in Figures 11 and 10 and as best shown in Figure 9 I form the spring members 68 on straight lines instead of curving them to conform with the wall 2 of the box. This is for the purpose of keeping the arms straight so that they can best respond as torsion springs to the inserting of the coins. As best shown in Figure 10 these arms 68 are substantially of 55 the same width as the bars 65 and 66 and

these bars are slightly narrower at their middle portions than at their ends to provide space between the lower bar and the bottom of the box and between the upper bar and the underside of the rotatable member to receive portions of the spring forming hooks for retaining the springs in position. For the purpose of providing the projections which guard the coin slot I provide a lateral prong 72 extending inwardly 70 from the free end of each arm 68 which are adapted to be turned inwardly or away from the shell of the box thus providing a tapered opening between them for the entrance of the coin. As the coin is entered thru the slot 18 against the prongs 72 the spring arms 68 are forced inwardly into inclined positions as shown by dotted line in Figure 14 spreading the prongs 72 apart and permitting the coin to enter freely into the coin 80 box. To prevent the coin distorting the springs and carrying them thru the opening in the support 61 I provide outwardly extending projections 73 on the free ends of the arms 68 adapted to be formed into hooks 85 for engaging the upper and lower edges of the bars 65 and 66 respectively. As best shown in Figure 14 it will be seen that if a coin is projected against the inner ends of the projections 72 from within the box it 90 will press directly against the said ends and press the spring arms 68 outwardly against the wall of the box and as they cannot yield any farther the opening between them cannot be made large enough to permit the 100 escape of a coin. The hooks 73 are freely movable around the outer edges of the bars 65 and 66 and the springs are free to respond to the pressure of the coin to permit the coin to enter the box but cannot be distorted too 105 much as they are pressed against the bars 65 and 66.

Preferably for making the projections 72 at the inner ends of the arms 68 long enough to form suitable curved guards for the coin slot I make the member 67 in the flat form shown in Figure 12 the arms 68 being outwardly inclined relatively to each other spreading their outer ends apart so that by severing the bar connecting their outer ends 110 I provide prongs of sufficient length. In Figure 13 I have shown a modified manner of producing prongs of sufficient length without the necessity of outwardly inclining the arms in their process of manufacture. 115 In this form the two prongs 72 on the members 67 are offset from each other so as to enable me to make each prong the full length from arm to arm thus avoiding the necessity of forming the member 67 after 120 the production of the arm to bring the arms 68 parallel with each other and reducing the width of metal necessary from which to produce the spring members. It will be understood that after the member 67 has 125 130

been formed as shown in Figure 12 the arms are made parallel by crimping up the portion 74 between the arms at their connected ends in a manner familiar to those skilled 5 in the art of manufacturing metal articles.

In Figure 22 I have shown a modified form of locking device. In this form I provide a stationary U-shaped guard ring 75 having an outer flange 76 turned up at its

- 10 edge and an inner flange 77. The outer flange 76 is adapted to contact with the body flange 4 adjacent to the outer wall 2 of the box and the inner flange 77 to contact with the cover 5 just within the 15 cover lugs 7 and thus form a solid and rigid guard for the locking member providing a suitable flat ring-like channel 78 in which the locking member freely rotates. In this form the inner locking ring 79 which takes 20 the place of the guard ring in the first form is provided at its outer edge with an upturned flange 80 adapted to contact with a flat tumbler or locking ring 81 at its outer edge the two rings 79 and 81 being spaced 25 apart for receiving the locking lugs 7 between them and these rings being formed similar to the rings already described for interlockment with the cover lug and provided with suitable notches for registering 30 with the notches in the flange 4 for receiving and releasing the cover lugs. In this form the stationary guard ring 75 is provided with a suitable opening 82 in proper relation to the coin slot 18 for receiving the 35 key projection 47 for releasing the cover lug from the spring 35 in the manner already described. Preferably I interlock the ring 79 with the ring 81 by means of interlocking lugs 83 and 84 similar to the 40 interlocking lugs 31 and 32 already described in relation to the rings 26 and 21.

The stationary guard ring 75 is forced into position and is formed to fit so tightly within the wall 2 of the box that it requires 45 no other fastenings and I can dispense with the legs 59.

It will now be seen that the guard ring whether stationary or rotatable protects the locking ring against the pressure of the 50 contents of the container and the contents of the container are protected by the guard ring from the cover lugs.

It will now be understood that I have provided a very simple means of locking the 55 cover upon a box leaving the cover rotatable and simulating a permutation or combination lock in that the cover can rotate to any extent in either direction when interlocked with the rotatable member and cannot be freed from the box until unlocked by means of the key and furthermore that the construction is simple and provides a box in which no protuberances are movable in contact with the coins as such protuberances 60 tend to bunch the coins or wear upon them

and are particularly objectionable when the box is used for the storage of jewelry or such like delicate expensive articles.

As many modifications of my invention will readily suggest themselves to those 70 skilled in the art I do not limit or confine my invention to the specific details of construction and operation herein described and claimed.

I claim:

1. In a device of the kind described, a casing open at one end, a circular cover member for said open end, a rotatable locking ring member within the casing, locking lugs on the cover, the casing and the rotatable member provided with notches through which the lugs pass in the application of the cover to the casing, the initial rotation of the cover being adapted to place the lugs 80 out of register with the notches in the rotatable member, and releasable means for locking the cover lugs to the rotatable member with its lugs out of registry with the notches 85 therein.

2. In a device of the kind described, a 90 closed casing having a circular opening bordered or defined by a flange, the flange provided with notches in its inner edge, a cover for said opening having L-shaped lugs adapted to pass through said notches and 95 enter beneath the flange, a rotatable locking member beneath the flange having notches adapted to register with the notches in the flange for permitting the passage of the cover lugs, the initial rotation of the cover 100 after application to the casing being adapted to position the cover lugs out of registry with the notches in the rotatable member, yielding means for locking the lugs to the 105 rotatable member with the lugs out of register with the notches therein, the rotatable member being freely rotatable with the cover in either direction, and means applicable to the casing for releasing the cover lugs from the rotatable member to permit 110 the registry of the lugs with the notches for opening the casing.

3. In a device of the kind described, a closed casing having a circular opening bordered or defined by a flange, the flange provided with notches in its inner edge, a cover for said opening having L-shaped lugs adapted to pass through said notches and enter beneath the flange, a rotatable locking member beneath the flange having notches 115 adapted to register with the notches in the flange for permitting the passage of the cover lugs, the initial rotation of the cover after application to the casing being adapted to position the cover lugs out of registry 120 with the notches in the rotatable member, yielding means for locking the lugs to the rotatable member with the lugs out of register with the notches therein, the rotatable member being rotatable with the cover in 125 130 135

- either direction, means carried by the rotatable member for frictionally engaging the casing to resist the free rotation thereof, and means applicable to the casing for releasing the cover lugs from the rotatable member to permit the registry of the lugs with the notches for opening the casing.
4. In a bank of the kind described, a casing having a circular opening, a cover section for closing said opening, lugs on the cover for projecting into the casing through said opening, means within the casing for interlockment with the lugs to prevent the removal of the cover, the cover when locked against removal being freely rotatable in either direction.
5. In a bank of the kind described, a casing having a circular opening, a cover section for closing said opening, lugs on the cover for projecting into the casing through said opening, a rotatable ring member within the casing for interlockment with the lugs to prevent the removal of the cover, means carried by the ring for frictional engagement with the casing to prevent any but intentional rotation thereof, the cover when locked to the ring member being freely rotatable therewith in either direction.
6. In a container of the kind described, a casing having a circular opening in its top and provided with notches extending out from the opening, a cover, horizontally extending lugs on the inside of the cover adapted to pass through said notches and engage beneath the top of the casing, rotatable means beneath the top of the casing for engagement with the lugs and adapted to prevent the escape of the lugs through the notches, the cover when engaged to the holding means being easily rotatable in either direction.
7. In a container of the kind described, a casing having a circular opening in its top and provided with lug-receiving notches in said top, a cover having outwardly extending lugs adapted to pass through the notches and engage beneath the top when the cover is rotated, a rotatable ring member beneath the top having notches adapted to register with the notches in the top to permit the passage of the lugs, means carried by the ring for engaging one of the lugs when the cover is rotated to position the lugs relatively to the ring out of registry with the notches therein, the ring and cover when engaged being easily rotatable together.
8. In a container of the kind described, a wall having a circular opening, a cover larger in diameter than the opening, outwardly extending lugs on the inside of the cover, the wall of the opening having notches to receive the lugs, a rotatable ring member within the cover having notches adapted to register with the notches in the
- wall of the casing to permit the entrance of the lugs, a shoulder on the ring member circumferentially spaced from a notch therein adapted to be engaged by one of the cover lugs, a locking spring for holding the lug in engagement with the shoulder and with the several lugs out of registry with the notches in the ring, and means for releasing the lug from the spring.
9. In a container of the kind described, a wall having a circular opening, a cover larger in diameter than the opening, outwardly extending lugs on the inside of the cover, the wall of the opening having notches to receive the lugs, a rotatable ring member within the cover having notches adapted to register with the notches in the wall of the casing to permit the entrance of the lugs, a shoulder on the ring member circumferentially spaced from a notch therein adapted to be engaged by one of the cover lugs, a locking spring for holding the lug in engagement with the shoulder and with the several lugs out of registry with the notches in the ring, the casing provided with a coin slot and means adapted to be projected through the coin slot for releasing the lugs from the rotatable member.
10. In a device of the kind described, a casing having a circular opening, a cover for the opening, outwardly extending lugs on the inside of the cover, the wall of the casing having notches opening into the said opening, a rotatable ring member within the casing in contact with the wall having the opening, notches in the ring adapted to register with the notches in the wall to admit the cover lugs, a shoulder on the ring adapted to be engaged by one of the lugs, a spring having a bend adapted to engage the edge of the lug opposite the said shoulder, the spring having a relatively inclined portion adjacent to said bend adapted to be engaged by the lug to force the spring outwardly to permit the lug to pass the bend, and means for applying a key to said inclined part of the spring for releasing the lug.
11. In a device of the kind described, a rotatable ring locking member, a flange at the outer edge of the ring, the flange fitting freely within the casing, a spring carried by the ring having a part adapted to project through the flange and which engages the wall of the casing to frictionally hold the ring against free rotation.
12. In a device of the kind described, a rotatable cover lug locking member, comprising a guard ring and a tumbler ring, the two joined into a unitary structure providing an annular ring-like space between them for the reception of the cover lugs.
13. In a device of the kind described, a rotatable cover lug locking member, comprising a guard ring and a tumbler ring, the

two joined into a unitary structure providing an annular ring-like space between them for the reception of the cover lugs, and means for rotatably supporting the rotatable member in contact with the top of the casing.

14. In a device of the kind described, a rotatable cover lug locking member, comprising a guard ring and a tumbler ring, 10 the two joined into a unitary structure providing an annular ring-like space between them for the reception of the cover lugs, and means carried by the rotatable member for engaging the casing with a frictional 15 engagement.

15. In a device of the kind described, a casing, one wall having a circular opening and provided with notches for the entrance of cover lugs, a cover for the casing, lugs on 20 the cover adapted to pass through said notches and upon rotation of the cover to engage beneath said wall, a guard member within the casing having a flange extending through the opening to contact with 25 the cover, and a flat circular part extending outwardly to the casing, and means for rigidly spacing the outer edge of the latter part from the wall having the opening.

16. In a coin bank, a slot through which 30 the coins can be inserted, a coin slot guard within the bank comprising a rigid support having bars parallel with and spaced at each side of the slot, torsion spring members on said support having projections extending into the path of the coins adapted to be turned inwardly out of the path of the coins as they are passed through the slot, and adapted to engage the casing of the bank to prevent their being turned in the opposite 40 direction out of the path of the coins when it is attempted to eject the coins through the slot.

17. In a coin bank having a coin slot, a coin slot guard within the casing adjacent 45 to the slot, consisting of a rigid support having bars arranged parallel with and spaced at each longitudinal edge of the slot, the bars presenting transversely inclined surfaces to the slot and forming a tapered coin chute in the casing beyond the slot, torsion 50 springs carried by the support having arms substantially coincident with said bars, each arm having a projection extending into the path of the coins as they are entered into the casing, means for holding said arms against the too great displacement, said arms adapted to be twisted as the coins pass in to carry said projections out of the 55 path of the coins, the twisting of the arms being limited by the adjacent inclined bars.

18. In a coin bank having a coin slot, a coin slot guard within the casing adjacent to the slot, consisting of a rigid support having bars arranged parallel with and spaced 60 at each longitudinal edge of the slot, the

bars presenting transversely inclined surfaces to the slot and forming a tapered coin chute in the casing beyond the slot, torsion springs carried by the support having arms substantially coincident with said bars, each 70 arm having a projection extending into the path of the coins as they are entered into the casing, means for holding said arms against the too great displacement, said arms adapted to be twisted as the coins pass 75 in to carry said projections out of the path of the coins, the twisting of the arms being limited by the adjacent inclined bars, and oppositely extending projections on the free ends of the spring arms adapted to hook 80 over the outer edges of the rigid bars to prevent the coin from distorting the springs beyond their resiliency.

19. In a coin bank, a casing having a circular opening at its top, a cover section for 85 closing said opening, L-shaped lugs on the inside of the cover adapted to be projected through said opening into the casing, a rotatable lug-locking ring member in the casing for engagement with said cover lugs, 90 and means rigid with the bottom of the casing and upstanding therefrom for rotatably supporting the lug-locking ring.

20. In a coin bank, a casing having a coin slot, a coin slot guard within the casing 95 rigidly supported on the bottom of the casing and upstanding therefrom.

21. In a coin bank of the kind described, a casing having a coin slot, a coin slot guard within the casing adjacent to the slot, the 100 guard secured to the bottom of the casing only and upstanding therefrom.

22. In a bank of the kind described, a casing having a coin slot, a coin slot guard within the casing comprising a rigid supporting member rigidly mounted adjacent to the coin slot, and a sheet metal spring member secured on each end of the support, each member having two tortional spring arms extending toward the middle of the 110 coin slot, each arm having a curved projection extending into the path of the coins.

23. In a bank of the kind described, a casing having a coin slot, a coin slot guard within the casing comprising a rigid supporting member rigidly mounted adjacent to the coin slot, and a sheet metal spring member secured on each end of the support, each thereof having two tortional spring arms extending toward the middle of the coin slot, each arm having a curved projection extending into the path of the coins, each arm also provided with projections adapted to be bent over the outer edges of the rigid support for preventing destructive distortion of the arms 120 by the coins.

24. In a bank of the kind described, a casing having a circular opening in its top, a cover for said opening, locking lugs on the cover, the top having notches through 130

which the lugs are projected, a rotatable locking ring member within the casing having notches through which the cover lugs pass, and stops on the locking ring for engagement with the cover lugs when rotated in one direction to cause the lugs to register with the notches in said ring.

25. In a bank of the kind described, a casing having a circular opening in its top, 10 a cover for said opening, locking lugs on the cover, the top having notches through which the lugs are projected, a rotatable locking ring member within the casing having notches through which the cover lugs 15 pass, stops on the locking ring for engagement with the cover lugs when rotated in one direction to cause the lugs to register with the notches in said ring, and shoulders on the ring spaced from the stops to permit the 20 lugs to move out of register with the notches in the ring when the cover is rotated relatively to the ring in the opposite direction.

26. In a bank of the kind described, a casing having a circular opening in its top, 25 a cover for said opening, locking lugs on the inside of the cover, the top having notches at the edge of the opening for receiving

the lugs, a rotatable lug-locking ring within the casing having notches for receiving the cover lugs, stop shoulders on the ring member 30 permitting the cover lugs to be moved out of register with the notches in the ring, and releasable means carried by the ring member for holding the lugs against said stop shoulders.

27. In a bank of the kind described, a casing having a circular opening in its top, a cover for said opening, locking lugs on the inside of the cover, the top having notches at the edge of the opening for receiving the 40 lugs, a rotatable lug-locking ring within the casing having notches for receiving the cover lugs, stop shoulders on the ring member permitting the cover lugs to be moved out of register with the notches in the ring, 45 and a spring forming a latch for releasably holding the lugs against said shoulders, said spring adapted to cause the ring member to frictionally engage the casing to resist the free rotation thereof. 50

Signed at Chicago, Illinois, this 1st day of March, 1921.

GEORGE B. KEPLINGER.
